UNITED STATES PATENT OFFICE.

VYVYAN E. DONNER, OF NEW YORK, N. Y.

SIGN FOR ADVERTISING AND OTHER DISPLAY.

Application filed August 1, 1924. Serial No. 729,434.

To all whom it may concern:

Be it known that I, VYVYAN E. DONNER, a citizen of the United States of America, residing at borough of Manhattan, city, county, and State of New York, have invented certain new and useful Improvement in Signs for Advertising and Other Display, of which the following is a specification.

10 This invention relates to signs for advertising, display, publicity, promotion and similar purposes.

Pursuant to the preferred forms of my invention, the sign comprises a stationary or movable pictorial representation, alone or accompanied by lettering or other descriptive matter, for advertising or displaying merchandise, goods, theatrical or other shows and the like. Such pictorial representations are formed of multiple, separable parts, superimposed or fitted in or otherwise assembled or joined to one another to form the stationary or movable pictorial representations. The parts are assembled by the use of suitable securing elements, such as nails, screws, metal or wooden pins, or the like, or by spot welding or soldering when the parts are made of metal, or by the use of glue, cement, or like adhesive medium, when the parts are made of canvas, carboard or other paper stock and the like. The effects of relief or intaglio are attained by selecting different thicknesses for the respective parts or otherwise in the assembly of the representation.

The parts may be colored by dipping to cover the whole or selected portions of the individual parts; the parts can be colored to attain the desired color effect by stenciling, painting with brushes, or by airbrush, or other methods.

The separability of the parts is advantageous in the manufacture of the signs in quantity, and in the shipment of the parts to the locations of display, and for disassembly for removal to other locations.

Further features and objects of my invention will be more fully understood from the following detail description and the accompanying drawings, in which—

Fig. 1 is a front elevation of a sign showing diagrammatically one form of my invention and an advertisement of any desirable brand of goods, such as stockings;

55 Fig. 2 is a sectional elevation on line 2—2 of Fig. 1;

Fig. 3 is a top perspective view of a portion of the sign shown in Fig. 1, on an enlarged scale;

Fig. 4 is a top perspective view of another portion of the sign shown in Fig. 1, on the same enlarged scale as Fig. 3;

Fig. 5 is a detail perspective view of certain individual separated parts of the sign shown in Fig. 1, on the same enlarged scale as Figs. 3 and 4; and

Fig. 6 is a detail perspective view similar to Fig. 5, but showing a modification.

Referring to the embodiment of my invention shown in Fig. 1, the sign is typical in advertisement of any selected make of stockings, as representative of a brand of goods, and it will be understood that the character of pictorial representation and descriptive matter shown in Fig. 1 is applicable for similar and other types of goods, merchandise, commodities, theatrical and other shows and other things of value.

Referring to the drawings, the particular pictorial representation comprises the background member, 10, which may be a board integral for its full length and width, or of sectional parts, or a wall or other form of support. Upon the background 10, is built up the desired representation of the individual parts assembled in accordance with my invention.

In the particular pictorial matter of the sign illustrated in the drawings, a flight of steps is formed of a part or groups of parts, 11, having a thickness, see Fig. 2, applicable to show the desired relief. The pictorial representation shown in Fig. 1, further comprises the representation 12, of a maiden wearing the advertised merchandise, and preferably in a posture featuring the advertised merchandise. In this instance, the feature of a stocking is emphasized by the showing of one leg, 14, covered by a stocking, and the slipper, 15, cast away in the flight of the maiden down the steps, 11. In the particular representation of the sign shown in Fig. 1, the name "Annabelle stockings", an arbitrary brand, has been assumed, for which purpose the lettering, 16, appears as a legend on the sign, disposed at any suitable location such as at the top of the sign.

Such lettering, 16, may be formed of blocked individual letters, integral with or applied to a suitable base, 17 secured to the background base, 10.

The representation, 18, of a moon, colored blue or green or otherwise as desired, adds a touch of ornamentation to the posture of the maiden, 12.

5 The part 12, in representation of the maiden is shown formed of separable parts, superimposed or fitted within one another and of varying thicknesses to emphasize the desired relief or intaglio effects. Thus, the 10 part, 19, representing the face and the neck of the maiden, 12, see Fig. 3, is of a selected thickness to be set in relief relative to the face of the background base, 10. The part 15 20 represents the wig of the maiden 12, which is of a proper or selected thickness and as illustrated may be fitted at its marginal line 20^a of a suitable curved contour to a similarly curved marginal line of the face part 19. The wig part 20, may be of 25 greater thickness than the face part 19, as illustrated, whether fitted or superimposed, or the parts 19, 20 may be of substantially the same thickness.

In a like manner, the part, 21, representing 25 the waist of the maiden 12, is selected of a proper thickness and fitted at its intersecting line 22 with the neck portion of the part, 19. The part, 23, in representation 30 of the left arm is of a different thickness from that of the waist part, 21, and of the face and neck part, 19.

In the representation, the maiden, 12, is shown holding a pannier, constituted of an individual part, 24, separable from the 35 remaining parts and is selected in thickness to effect the desired presentation of being held by the hand part, 25, representing the left hand, for which purpose the hand part, 25, is cut away at its rear face, as indicated at 26, to receive the scarf part, 24. It will be also noted that the scarf part, 40 24, is fitted at its line of contour, indicated at 28 to and within the lower portion, 29, of the arm part, 23.

45 In a like manner, the remainder of the figure is superimposed or fitted in, or both, relative to the adjacent parts. The skirt part, 30, see Figs. 3 and 4, is selected of a proper thickness and its lower margin, 50 31, is fitted to the lining part, 32, of a reduced thickness; the leg part, 14, is shown of a greater thickness than the lining part, 32, but of less thickness than the skirt part 30, to attain the relief represented in the 55 illustration. It will be noted that the lining part, 31, is fitted at its marginal line, 34, to the leg part, 14, and that the skirt part 30 is fitted at its front portion 35, to the leg part, 14.

60 In Fig. 5, the arm part, 23, is shown separated from the pannier part, 24, to illustrate its hand portion, 25, cut away at 65 26 to receive within its cut away portion 26 the portion, 27 of the pannier part, 24, similarly as shown in Fig. 3.

To attain substantially the same relief and intaglio effects, such parts may be assembled as is indicated in Fig. 6, namely the arm part, 23, to have its hand part, 36, of a uniform thickness as indicated at 37 70 and the pannier part, 24, of a uniform but less thickness and cut out as indicated at 38 to receive the arm portion 36 of a greater thickness as indicated at 37, to thereby derive the desired visual effect attained by 75 the alternative arrangement shown in Figs. 3 and 5.

It will be understood that the background 10 may be colored appropriately of one or more colors, and may be built 80 of separately colored sections as desired. The individual sections of the background 10 may be colored of a single solid color or a plurality of different solid colors.

From the above, it will be perceived that 85 the parts of the figure or other pictorial representation applied to the background, are formed of individual parts, superimposed or fitted or otherwise compositely 90 assembled, each part being colored in whole or in portions of solid color. The color scheme of the sign as a whole is preferably selected to enhance the desired relief or intaglio effect, and to obtain prominence of 95 the representation of the goods or merchandise, or of an incident of a theatrical or other show, or the like, featured by the sign.

For the purpose of manufacture in quantities, the parts of the pictorial representation, descriptive matter and adjunct parts, 100 may be colored by dipping each part in whole or in portions in the coloring. The coloring may be applied by brush, or by spraying or by a so-called air brush, or by 105 stenciling or other suitable methods.

The background may be made of wood, or of sheet or other forms of metal and the like. The parts of the pictorial, descriptive and adjunct representations formed of 110 wood may be shaped by jig-saws, or rotary saws and by other suitable methods. The parts may be formed of canvas, cardboard or other paper stock or of moldable composition or other suitable material.

The parts may be assembled at the location of display to form the sign by means of nails, screws, wooden or metal pins, rivets, or by spot-welding, or by application of glue or the like, determined by the 115 nature of the materials of the parts and the desired permanence of installation.

The separability of the parts affords simplicity of manufacture and facilitates the shipment of the parts to the locations of 120 assembly. The parts may be sectioned to attain standard sizes when bundled together for shipment or transportation.

The assembly of the parts may be carried out by the use of diagrams to indicate 125 130

the respective positions of the parts on the composite sign.

The invention is also applicable for signs having one or more parts movable relative to other parts or to the background of the sign.

Whereas I have described my invention by reference to specific forms thereof it will be understood that many changes and modifications may be made without departing from the spirit of the invention.

I claim:

1. A pictorial representation for advertising and other display purposes, comprising a plurality of separate members representing separate parts compositely forming the pictorial representative, certain of said members being superimposed upon one another, and certain others of said members having different thicknesses relative to one another to attain the desired relief and intaglio effects.

2. A pictorial representation for advertising and other display purposes, comprising a plurality of separate members representing separate parts compositely forming the pictorial representation, certain of said members being superimposed upon one another, and said members having thicknesses relative to one another to attain the desired relief and intaglio effects, a background and means for securing said members to one another and to said background.

3. A pictorial representation for advertising and other display purposes, comprising a plurality of separate members representing separate parts compositely forming the pictorial representation, certain of said members being superimposed upon one another, and said members having thicknesses relative to one another to attain the desired relief and intaglio effects, a background and removable means for securing said members to one another and to said background.

4. A pictorial representation for advertising and other display comprising a plurality of separate members representing separate parts compositely forming the pictorial representation, certain of said members being superimposed upon one another and of different thicknesses to attain the desired relief or intaglio effects.

5. A pictorial representation for advertising and other display comprising a plurality of separate members representing separate parts compositely forming the pictorial representation, certain of said members being fitted in relative to one another and of different thicknesses to attain the desired relief or intaglio effects.

6. A pictorial representation for advertising and other display comprising a plurality of separate members representing separate parts compositely forming the pic-

torial representation, certain of said members being superimposed upon one another and other said members fitted in relative to one another, said members being of different thicknesses to attain the desired relief or intaglio effects.

7. A pictorial representation for advertising and other display purposes comprising a plurality of individual members of different thicknesses, certain of said members being superimposed upon one another and removable means for attaching said members to one another to compositely form the pictorial representation.

8. A pictorial representation for advertising and other display purposes comprising a plurality of individual members having different thicknesses, certain of said members being superimposed upon one another, a background and removable means for securing said members to one another and to said background.

9. A pictorial representation for advertising and other display purposes comprising a background, a plurality of separate members of different thicknesses, said members being individually of solid colors and means for securing said members to one another and to the background to compositely form the pictorial representation.

10. A pictorial representation for advertising and other display purposes comprising a background, a plurality of separate members of different thicknesses, said members being individually of different solid colors and means for securing said members to one another and to the background to compositely form the pictorial representation.

11. A pictorial representation for advertising and other display purposes, comprising a plurality of separate members representing separate parts compositely forming the pictorial representation, certain of said members being superimposed upon and interfitted with one another, and said members having thicknesses relative to one another to attain the desired relief and intaglio effects.

12. A pictorial representation for advertising and other display purposes, comprising a plurality of separate members representing separate parts compositely forming the pictorial representation, certain of said members being superimposed upon and interfitted with one another, and said members having thicknesses relative to one another to attain the desired relief and intaglio effects, a background and means for securing said members to one another and to said background.

In testimony whereof I have signed this specification this 17th day of July, 1924.

VYVYAN E. DONNER.
